ABSTRACT OF THE DISCLOSURE

A rotary extrusion-type pellet mill wherein a roller cooperating with a rotating die is forcibly rotated by a gear provided on the surface thereof in engagement with a gear provided on the inside wall surface of said rotating die and the interior of said roller is maintained pressurized by a pressure fluid supplied therein from the rear end of a roller supporting shaft throughout the period of operation, whereby a lowering of extruding capacity and formation of unsatisfactory product due to idling or binding of the roller as has been experienced in a conventional mill of this type can be eliminated.

BACKGROUND OF THE INVENTION

Field of the invention

The present invention relates to an improved extrusion-type pellet mill for wet powdery materials.

Description of the prior art

A conventional extrusion-type pellet mill is so constructed that a roller disposed in a rotary hollow cylinder having a multiplicity of apertures bored through the wall thereof rotates in sliding contact with the inside wall surface of said hollow cylinder, and a powdery material fed into said hollow cylinder is compressed between said roller and the inside wall surface of said cylinder and extruded through said apertures in the form of pellet.

The present inventors attempted to produce a pellet of a fertilizer, e.g. a high-analysis compound fertilizer, by extrusion using the conventional extrusion-type pellet mill of the construction described above and found that the conventional pellet mill had the following defects. Namely, in the conventional pellet mill, since the perforated hollow cylinder only is rotated and the roller is driven by said cylinder in sliding contact therewith, the roller frequently stops rotating by being bound by a powdery material being processed depending upon the type of material and as the result a satisfactory extrusion of the powdery material through the perforated wall of the cylinder cannot be obtained due to a lack of compressive force. In addition, since the conventional pellet mill resorts only to the compressive force for forcibly extruding the material through the apertures, the hollow cylinder is required to be rigid and tough sufficient to withstand the high pressure exerted thereon and accordingly a large power is consumed for the pellet-making operation.

Furthermore, in the operation of the conventional pellet mill, the powdery material being processed tends to intrude into a roller supporting mechanism housed in said roller, interfering with the smooth rotation of the roller or causing a malfunction of the same. In order to avoid such troubles, therefore, it becomes necessary to interrupt the operation every several hours and to force into the roller a lubricant, such as grease, and thereby to purge the powdery material from the roller along with said lubricant. By this reason, the conventional pellet mill is capable of continuous operation of only four or five hours at longest.

2

SUMMARY OF THE INVENTION

The object of the present invention is to provide a pellet mill which is free from the aforesaid drawbacks of the conventional one. The pellet mill of the present invention comprises a rotary, perforated, hollow cylinder having a gear formed integrally on the inner wall surface thereof, a roller disposed inside of said hollow cylinder and having a gear formed integrally on the outer surface thereof for engagement with the gear of said hollow cylinder, said roller being rotated forcibly by said rotary hollow cylinder through the engagement of said gears, whereby a powdery material fed in said hollow cylinder is extruded into the form of pellet through the perforated wall of said cylinder while being compressed and kneaded between said roller and said cylinder, and means for supplying and retaining a pressure fluid in the interior of said roller to prevent intrusion of the powdery material into said roller.

BRIEF DESCRIPTION OF THE DRAWING

FIG. 1 is a schematic view, in cross-section, of the pellet mill according to the present invention and FIG. 2 is a fragmentary cross-sectional view, in an enlarged scale, showing the engagement between a hollow rotary cylinder and a roller of the pellet mill shown in FIG. 1 and also the detailed structure of the roller.

DESCRIPTION OF THE PREFERRED EMBODIMENT

The present invention will be described in further detail with reference to the accompanying drawing.

Referring to FIG. 1, a powdery material fed from a supply hopper 1 is led into the interior of a perforated hollow cylinder 3 through a supply hood 2 connected to the front end wall of said cylinder 3. The perforated hollow cylinder 3 is mounted on a flange of a hollow rotary shaft 6 through a fixture 5, and rotated by said hollow rotary shaft 6 when the latter is driven by a prime mover not shown. A roller 4 is disposed in the cavity of the perforated hollow cylinder 3 in contact with or in slightly spaced relation to the inside wall surface of said cylinder, and secured to roller supporting members 9, 10 fixed on a fixed rod 7.

As shown in FIG. 2, the perforated hollow cylinder 3 is provided with a gear 16 at a portion thereof, while a cooperating gear 17 is provided on the surface of the roller 4, the arrangement being such that when the perforated hollow cylinder 3 is rotated, the roller 4 is driven at a predetermined speed ratio. The fixed rod 7 has an axial bore 8 extending therethrough and this axial bore is in communication with the interior of the roller 4 through an oil supply tube 11 and an oil supply passage 13 formed in a roller shaft 12. Thus, it will be understood that a fluid compressed by fluid compressing means not shown and fed into the axial bore 8 from one end thereof, is supplied into the interior of the roller 4. The fluid introduced into the roller 4 is retained therein at a predetermined pressure by means of pressure retaining rings 14, 15 provided in said roller.

According to the present invention wherein the roller is driven forcibly by the perforated hollow cylinder at a predetermined speed ratio as described above, binding of the roller can be prevented and further the powdery material being processed is subjected to not only compression but also a suitable degree of kneading action, so that the power consumption can be reduced markedly compared with the conventional device.

Further, according to the present invention, intrusion of the powdery material into the interior of the roller can be prevented completely by the pressure fluid supplied and retained in said roller and thereby the present pellet mill is capable of continuous operation for a period rang-

ing from at least one week to several weeks, compared with the conventional pellet mill which is capable of continuous operation for only several hours.

By employing the pellet mill of this invention, it is possible to granulate powdery materials, e.g., urea high-analysis compound fertilizers, the granulation of which has been almost impossible by the conventional extrusion granulating method. As is obvious, the pellet mill of the present invention is applicable to the mass production of a pellet of not only fertilizers but also many other similar powdery materials, such as animal feeds, agricultural chemicals and catalysts.

Examples provided below show a comparison between the performance of the present pellet mill and that of the conventional one, when used for the granulation of fertilizers. Examples 1 and 2 are the cases wherein the roller was rotated forcibly, whereas the Control Example is the

Diameter of perforations in the hollow cylinder: 2.0 mm. Operating power: 0.04 kw./kg.

In Examples 1 and 2, the pellet mill was continuously operated for 70 hours while maintaining the fluid in the roller at a pressure of 3 kg./cm.² and after the operation no change was observed interior of the mill, whereas in the control example, the pellet mill went slightly out of order after 2 hours of continuous operation and became inoperative after 3 hours. Upon overhaul the mill, it was revealed that the roller had been bound by the fertilizer and further a large amount of fine fertilizer powder was present in the rotating mechanism of the roller.

EXAMPLE 3

Powdery material used

The high-analysis compound fertilizer as used in Example 1.

Fluid pressure in the roller.....	0 kg./cm. ² G.....	0.2 kg./cm. ² G.....	3 kg./cm. ² G.....
Period of continuous operation.....	3 hours.....	6 hours.....	70 hours.....
Amount of fertilizer powder intruded into the roller.....	Large.....	Slight.....	None.....

case wherein the roller was let to slidably contact the cylinder. Example 3 is the case wherein a pressure fluid was supplied and retained in the roller during the operation.

EXAMPLE 1

Powdery material used

	Ingredient	Unit	Weight percent
Potassium chloride.....	60	258	25.1
Urea.....	46	265	25.7
Ammonium sulfate.....	21	95	9.2
Double superphosphate.....	38	407	40.0
Water.....		4 percent	

Roller peripheral speed/hollow cylinder peripheral speed: 1.10

Thickness of the hollow cylinder: 15 mm.

Diameter of perforations in the hollow cylinder: 2.0 mm.

Operating power: 0.025 kw./kg.

EXAMPLE 2

Powdery material used

Organic fertilizer composed of:

	Percent
Crude protein.....	29
Crude fat.....	3
Crude fiber.....	0
Crude ash.....	9
TDN.....	69

Roller peripheral speed/hollow cylinder peripheral speed: 1.02

Thickness of the hollow cylinder: 15 mm.

Diameter of perforations in the hollow cylinder: 2.0 mm.

Operating power: 0.02 kw./kg.

CONTROL EXAMPLE

Powdery material used

The same high-analysis compound fertilizer as used in Example 1.

Roller peripheral speed/hollow cylinder peripheral speed: 1.0 (The roller was rotated by sliding contact with the cylinder.)

Thickness of the hollow cylinder: 25 mm.

In this example, a mixture of a lubricant and air was used as the pressure fluid to be supplied into the roller.

What we claim is:

1. An extrusion-type pellet mill wherein one or a plurality of rollers are disposed in the cavity of a hollow rotary cylinder having a number of apertures perforated through the wall thereof and rotated therein for thereby extruding a powdery material through said apertures in the form of pellet, said pellet mill comprising a gear provided on the surface of each one of said rollers, a gear provided on the inside wall surface of said hollow cylinder and intermeshing with said first gears on the respective rollers thereby to forcibly rotate said rollers at a predetermined speed ratio as said hollow cylinder rotates, and means for supplying a pressure fluid into the interior of each one of said rollers and retaining the same interior of said roller thereby to prevent intrusion of the powdery material into the interior of said roller during operation of the pellet mill.

2. An extrusion-type pellet mill comprising a rotary perforated cylinder as a die ring, one or a plurality of rollers rotatable within said die ring, gear means for rotating said rollers in engagement with said die ring, said gear means comprising a gear provided on the outer surface of said rollers and a gear provided on the inner surface of said die and being so arranged that said gears may intermesh with each other to forcibly rotate said rollers at a predetermined speed ratio as said die ring is drive.

3. An extrusion-type pellet mill as claimed in claim 2 and further including means for supplying a pressure fluid into the interior of each of said rollers, to prevent the powdery material from intruding into the interior of said rollers during operation of the pellet mill.
